UNITED STATES PATENT OFFICE.

WILHELM BISDORF, OF BARMEN, GERMANY, ASSIGNOR TO THE FIRM OF A. W. NAGEL,
OF BARMEN, GERMANY.

LACE-MAKING MACHINE.

1,032,373.

Specification of Letters Patent. Patented July 16, 1912.

Application filed September 6, 1911. Serial No. 647,962.

To all whom it may concern:

Be it known that I, WILHELM BISDORF, a subject of the German Emperor, and residing at Barmen, Germany, have invented certain new and useful Improvements in Lace-Making Machines, of which the following is a specification.

My invention relates to lace-braiding machines in which the number of bobbins is equal to the number of heads or plates, and a primary object is to provide a machine of this type for making lace comprising web-like spots.

For making patterned braids on braiding-machines it is well-known to employ special weft threads which are inserted between the shed-forming bobbin threads at right angles to the length of the braid produced by the bobbins. For forming these patterns, however, braiding machines are used comprising groups of heads arranged together in rows and connected by points, the bobbins being able to occupy shed-forming positions on the groups of heads, while under the braiding place are arranged two devices which are movable in the direction of the longitudinal axis of the machine and insert the weft.

In contradistinction thereto, by means of my improved lace-braiding machine, *i. e.* one comprising heads or plates arranged in a circle, the number of which is equal to the number of bobbins, the lace patterns being made by temporarily stopping the bobbins, web-like spots are made in or on the lace fabric by a shuttle which moves forward and backward along a circular race, or runs around in a circle above or below the braiding threads, and inserts the weft thread into the sheds made by lifting individual bobbin threads of stationary bobbins. These sheds are formed by jacquard pattern gear and the length of the path of the shuttle during its reciprocatory motion or the number of complete circuits of the same is likewise determined by a jacquard pattern gear which influences a device comprising reversing gear.

One illustrative embodiment of my invention is represented by way of example in the accompanying drawings, wherein:

Figure 1 shows my lace-braiding machine partly in elevation, and partly in vertical section through the middle. Fig. 2 represents, enlarged, a part of the machine in vertical section, and Fig. 3 a portion in top

plan view on the horizontal section according to A—B in Fig. 2. Fig. 4 is a front elevation, Fig. 5 a top plan view and Fig. 6 a section of the shuttle. Figs. 7 and 8 are front elevation and top plan view on the section according to C—D, respectively, of the change gear for the drive of the shuttle. Fig. 9 diagrammatically shows a lace-fabric having web-like spots woven therein.

Referring to the drawings, on the top plate *a* of the machine the bobbins *c* are moved in the race *b* in known manner and temporarily stopped according to the pattern to be obtained. A ring *h*, carried by bolts *g*, by a frame *g* above the machine, is arranged above the threads *f* of the bobbin spools which unite in the braid-ring *o* and are plaited on a mandril *d* which is likewise well known. The ring possesses at its lower edge a circular race *h*₁ for a shuttle *i* (Figs. 2 and 4 to 6) from whose spool *i*₁ the weft thread *i*₂ is likewise led to the ring *o*. On the stationary ring *h* is guided in a suitably turned guide a toothed rim *k* meshing with a number of gears *m* distributed at equal distances apart around the stationary ring *h*. Each of these gears is fast on an axle *m*₁ journaled in a bearing *m*₂, bolted to the outer periphery of the ring *h*. The lower end of this axle *m*₁ projects beyond the bearing *m*₂ and carries a second gear *n* which by meshing in a toothed rack *i*₃ of the shuttle drives the same in the race *h*.

The toothed rim *k* is rotated right-handedly or left-handedly by a pinion *p* (Fig. 1) fast on the axle *p*₁ which is suitably journaled in the frame *g* and rotated through the medium of a set of gears *p*₂, *p*₃, *p*₄, *p*₅ by a shaft *q*. Consequently the toothed rim *k* is rotated in a direction corresponding to the direction of rotation of this shaft, and consequently the shuttle, whose toothed rack *i*₃ constantly meshes with two of the gears *n*, is reciprocated.

The lower edge of the fixed ring *h* is provided with recesses *h*₂ at equal distances apart, each of which is above one of the bobbin threads *f* when the bobbin is at its stationary position. Further, under each recess is arranged a thread-raising device comprising a lifter *s* guided in a bracket *r* and a lever *t* connected with the lifter. When the lifter is moved upward by a corresponding rotation of the lever (dotted position Fig. 2) it catches the bobbin thread in a recess

s_1 provided at its upper end and brings the same, as shown in Fig. 2, into a position in which its portion located toward the ring o is over the shuttle i . The height of the recesses h_2 is such that the raised thread has sufficient room upward. The lifter has laterally depending wings s_2 which when descending prevent those threads of the adjacent bobbins being caught which are not raised but go to the ring o . According to the form shown the arms r are fast on a ring u which is carried by holders u_1 bolted to the top plate of the machine. The lifters are under the influence of a special jacquard pattern gear arranged at a suitable place in the machine, its hooks being connected by rods y and bell-crank levers y_1 with bell-crank levers z which are fulcrumed in a circle on a circular plate x under the lace-braiding machine and are connected by rods z_1 with the levers t .

The right-handed and left-handed rotation of the shaft q , which transmits its motion, as mentioned above, to the toothed rim k , is brought about by change gear which, according to the arrangement shown in the drawing, is arranged on the bottom plate of the machine and is represented in Fig. 1 in side elevation and in Figs. 7 and 8 on an enlarged scale. The one or the other of the clutch gears 1 and 2 can be caused to engage with the pinion q_1 on the shaft q ; these gears 1 and 2 are on clutch sleeves 3 and 4, respectively, which are arranged axially displaceable on the hubs of gears 5 and 6, respectively, under the pinion q_1 . When the gears 1, 2 are in their raised position, as is the case with gear 1 in Fig. 7, they are out of engagement with the pinion q_1 and each 40 is also disconnected from the appertaining gear 5 and 6. As clutching means catches 7 and 8 may serve which engage in corresponding recesses in the gears 1 and 2. Further, fast on the clutch sleeves 3, 4 are 45 projections 13, 14 extending over inclined ways 15, 16 which can execute short rotatory motions about pivots 17 and 18, respectively (Fig. 8). These rotatory motions are brought about by vertically movable, spring-lifted cones 19 and 20 to which are connected bolts 21 and 22, respectively, whose ends extend below the bottom plate of the machine. When moving downward the cones engage in corresponding bores 50 and 31, respectively of the arms carrying the inclined ways 15, 16 and press these laterally according to the slant of the walls of the cones against the action of springs 25 and 26, respectively, whereupon the inclined ways pass out of the path of the projections 13, 14.

The inclined ways bring about the lifting of the clutch sleeves when the ways are located in the path of the projections 13 or 60 14, as is shown for the way 15 at the left

of Figs. 7 and 8, the projections 13 running on the way 15 at the lowest part thereof, and moving upward during the subsequent rotation. This takes place until the gear 1 is disconnected from the pinion q_1 , the disconnection with the gear 5 having previously taken place. In the highest position the projections 13, 14 are stopped at stops 23, 24 provided at the end of the inclined ways.

In order specially to secure the elevated position of the gears 1 and 2 forks 9 and 10 may be provided engaging in grooves in the clutch sleeves, said forks being secured on bolts 11, 12 which are guided in the frame e of the change gear, and under which forks elastic catches engage which (not shown in the drawings) are so connected with the cones 19, 20 that they are disconnected when the cones descend.

The gears 5 and 6 meshing one in another and consequently rotating in opposite directions are maintained constantly rotating by a gear 27 driven by the machine. Now when one of the cones is pulled and the appertaining projection, *e. g.* 16 at the right hand of Figs. 7 and 8, is released, the clutch sleeves slide downward, the clutch is connected, and simultaneously the gear 2 on the sleeve meshes with the pinion q_1 and is consequently rotated. The shaft q is then rotated to the right in the direction shown by the arrow as long as the cone 20 is maintained in its lower position. If, however, after the gear 2 is disconnected from the pinion q_1 , the gear 1 meshes with the pinion q_1 , which occurs when the cone 19 is pulled, the shaft q is rotated in the opposite direction. If both the cones are in their highest position the shaft q is stationary.

The change in the position of the cones is brought about by the pattern gear M , *e. g.* Jacquard pattern gear, which can simultaneously serve for controlling the stopping devices of the bobbins, two hooks 28, 29 being connected with the bolts 21, 22 by suitably assembled rod- and -lever mechanism v and w mounted in the bottom frame of the machine.

Now the manufacture of web-like spots in the middle of lace as shown in Fig. 9 is obtained by a suitable number of the bobbin threads traversing the lace being used for forming the sheds by means of the lifters s . The suitable change of shed is brought about by the Jacquard pattern gear influencing the lifters, while the shuttle i is driven to and fro by the toothed rim k above the part of the bobbin race at which the bobbins braid the middle of the lace. The rotation of the toothed rim which guides the shuttle to or at the said place and the changing rotation in the one and in the other direction is brought about by the change gear in consequence of the corresponding adjustment.

of the cones by the pattern gear M in the above described manner. The shuttle thread i_2 (Fig. 9) is thereby woven with the bobbin threads until the desired length of the spots is obtained. The shuttle thread can then, as in the example Fig. 9, be guided by a correspondingly wide circuitous motion of the shuttle to the edge of the lace and on the way there be worked both into the edge by suitable formation of shed and into the lace fabric. In order to make the next spot the shuttle is guided again above the part of the bobbin race in question and there moved to and fro. The breadth of the spot is of course dependent on the length of the path along which the reciprocating motion of the shuttle takes place. After the last weft thread has been inserted, the shuttle can be stopped at the end of the race and the weft thread not plaited; this then simply runs in the braided fabric from one spot to another, as indicated in Fig. 9 in dotted lines.

It will be readily understood that the web-like formations may have the most various forms and be made at any desired parts in the lace. Also, patterns can be made superposed upon a lace ground-work when the lace-braiding machine possesses surplus bobbin places or, as is said, when the machine is worked with lacking spools. The shuttle can also run around repeatedly in one direction and, lastly, it may be noted that a second shuttle may be arranged opposite the outside shuttle, *i. e.* inside the ring mounted above the braiding threads, and be driven by inner toothed rim of the toothed rim. Further, two or more shuttles may be arranged one above another both inside and outside the ring.

40 I claim:—

1. The combination, with a lace-braiding machine comprising a plurality of heads or plates arranged in a circle, means for rotating the same, and a plurality of bobbins adapted to be driven by the heads or plates, of pattern-gear-controlled means for forming sheds of threads extending from temporarily stationary bobbins to the middle of the circle, a horizontal, circular shuttle race arranged in the plane of the said sheds, a shuttle movable in the said shuttle race, and means for driving the said shuttle to and fro in the said shuttle race.

2. The combination, with a lace-braiding machine comprising a plurality of heads or plates arranged in a circle, means for rotating the same, and a plurality of bobbins adapted to be driven by the heads or plates, of pattern-gear-controlled means for forming sheds of threads extending from temporarily stationary bobbins to the middle of the circle, a horizontal circular shuttle race

arranged in the plane of the said sheds, a shuttle movable in the said shuttle race, means comprising change gear for driving 65 the said shuttle to and fro in the said shuttle race, and pattern gear for controlling the said change gear.

3. The combination, with a lace-braiding machine comprising a plurality of heads or 70 plates arranged in a circle, means for rotating the same, and a plurality of bobbins adapted to be driven by the heads or plates, of pattern-gear-controlled means for forming sheds of threads extending from temporarily stationary bobbins to the middle of the circle, a ring having a race and vertical recesses mounted above the heads or plates, a shuttle movable in said race, a toothed rim 75 rotatably mounted on said ring, means 80 driven by said toothed rim for driving the said shuttle, and reversible gearing for rotating said toothed rim.

4. In a lace-braiding machine, the combination, with a frame, a plurality of heads 85 or plates arranged in a circle in the frame and forming therewith a race, means for rotating the heads or plates, and a plurality of bobbins adapted to be driven in the said race by the heads or plates, of a plurality of 90 lifters on the said frame for raising threads extending from stationary bobbins to the middle of the said circle and thereby forming sheds, pattern gear controlled means for actuating said lifters, a shuttle-race mounted above the heads or plates, a shuttle movable in the shuttle-race, and means for driving the shuttle in the shuttle-race.

5. The combination, with a lace-braiding machine, comprising a plurality of heads or 100 plates arranged in a circle, means for rotating the same, and a plurality of bobbins adapted to be driven by the heads or plates, of pattern-gear-controlled means for forming sheds of threads extending from temporarily 105 stationary bobbins to the middle of the circle, a ring having a race and vertical recesses mounted above the heads or plates, a shuttle movable in said race, a toothed rim 110 rotatably mounted on said ring, means driven by said toothed rim for driving the said shuttle, and reversible gearing for rotating said toothed rim; a plurality of brackets on said ring, a lifter comprising laterally depending wings guided in each 115 bracket, a lever fulcrumed on each bracket and pivotally attached to the lifter guided therein, and means for actuating the levers.

In testimony whereof, I affix my signature in the presence of two witnesses.
